UNITED STATES PATENT OFFICE.

CORNELIUS VANDERBILT, OF NEW YORK, N. Y.

RAILWAY-CAR.

SPECIFICATION forming part of Letters Patent No. 728,051, dated May 12, 1903.

Application filed April 18, 1902. Serial No. 103,533. (No model.)

To all whom it may concern:

Be it known that I, CORNELIUS VANDERBILT, a citizen of the United States, and a resident of the borough of Manhattan, city and

5 State of New York, have invented certain new and useful Improvements in Railway-Cars, of which the following is a specification.

My invention relates to railway-cars, and has for its object the provision of means 10 whereby the car-body may be supported by the bolsters and its weight distributed and applied to said bolsters at various points.

My invention also comprises an improved 15 form of bolster and other details of construction, as will be set forth.

My invention is not limited to the form of car shown, but may be used in other well-known forms of railway-cars, the scope of the invention being defined by the appended 20 claims.

In the drawings which accompany this specification similar reference-numerals indicate corresponding parts in the several views.

25 Figure 1 is a plan view of one half of the car, the other half being exactly similar thereto. Fig. 2 is a longitudinal vertical section of one-half of the car. Fig. 3 is a plan view of the end framework, showing the bolster and body-supports. Fig. 4 is a vertical half-section of the car at the bolster. Fig. 5 is a similar view on the line 5 5 of Fig. 2. Fig. 6 is a view similar to Fig. 3, but showing an alternative construction. Fig. 7 is a longitudinal vertical section of one-half of a car, showing the modification of Fig. 6.

In both of the cars illustrated the supporting-framework consists of two center sills 1 1, which may be and preferably are ordinary 40 rolled-metal channels. These sills extend the full length of the car. Resting upon the sills 1 1 and secured thereto are the bolster-beams 2 2, which may also be rolled-metal channels, as shown. Between the ends of these beams are secured the upright posts 3^a 3^a, shown as channels, upon which the body of the car is hung and which support a considerable portion of its weight. In order to distribute the weight of the car-body and the 45 load to be carried thereby more uniformly upon the bolster-beams 2 2, I secure upon

said beams a plate 3, having a portion 4 bent at an angle to the main body of the plate, so as to extend preferably at right angles to the sloping floor 5 of the car-body 6.

55

In the car shown in Figs. 1, 2, and 3 the plate 3 extends practically the entire width of the car. A beam 7, which may be a rolled-metal angle-beam, is secured to the bent portion 4 of the plate 3 along its entire length 60 and is preferably, although not necessarily, secured also to the car-body. The beam 7 furnishes a very light and yet a substantial support for the car-body along its entire width and distributes a considerable portion 65 of the weight thereof along the whole length of the bolster-beams.

In the car shown in Figs. 6 and 7 a plate 3', having a bent portion 4', is secured to the middle portion of the beams 2 2. To this plate 70 are secured the middle portions 8 8 of the bent angle-beams 7' 7'. The parts 9 9 of these beams extend up and down, diagonally across, and parallel to, the sloping floor of the car-body 6, as shown. It is evident that they form 75 a very extended support for the car-body and concentrate and apply a considerable portion of the weight thereof to those portions of the beams 2 2, which rest upon the center sills. It is also evident that either a single floor-beam may be secured to the upwardly-extending portion of the bent plate, as in Fig. 3, or a floor-beam may be secured upon each side of the plate, as in Fig. 6. It has been proposed heretofore to bend the free edge of 80 a supporting-plate, so as to form an integral supporting-flange for the sloping floor; but such a structure is inferior to mine in that the floor-support lacks the strength which is imparted to it by the metal composing one 85 flange of the floor-beams used by me. In the structure employed by me the bent plate which is attached to the bolster may, for this reason, be made of thinner metal than would necessarily otherwise be used. The bent plate 90 used by me is also less complex in shape than the structure referred to above and can be more easily produced.

In the type of car of which those shown are examples the center sills pass through the 100 body of the car. (See Figs. 2 and 7.) In order to properly incase these sills and at the

same time to cause the flooring of the car-body to slope at all points toward one of the four hoppers 10 10, I secure above the sills 1 1 the inclined bent plates 11 11, which are joined along their meeting edges 12 12 to form a peak above the sills. (See Figs. 1 and 5.) The inner walls of the hoppers 10 are composed of vertical plates 22, the upper edges of which are secured to the lower edges of the bent plates 11. It has been proposed heretofore to secure the lower edges of similar bent plates to the center sills; but it will be observed that in the car here shown the said plates are secured to the walls of the hoppers. 15 By my construction I am enabled to place the center-sill channels so as to face outwardly, and thereby obtain a plane securing-surface between them for the attachment of the bolster center bearings. Furthermore, the car-body may be removed from the framework without cutting the rivets which are placed through the lower edges of the plate 11 and less of the weight of the load is carried by the center sills than in previous structures. 20 25 The transverse center peak is formed by the floor-plates 17 17. These plates are laid upon the sloping floor-beams 18 and are provided with the vertical portions 20, bent upwardly. The vertical portions of the two plates abut 30 against each other along their entire length and are secured together. I prefer to secure the ends of the vertical portions 20 to the side walls of the car by means of the small angle-plates 21, thus bracing the peak and giving 35 it additional strength. The plates 11 and 17 may be readily rolled to the shapes shown.

The bolsters are completed by the center bearing-pieces 13, secured to the center sills, and the side plates 14 14, which are secured 40 to and depend from the beams 2 2. The lower edges of these plates carry the side bearings 15, which are secured between them, as shown. The plates 14 14 are also secured to the longitudinal end braces 30 by the angle- 45 plates 16.

It is found that when metal cars are damaged by collision the ends of the cars are frequently bent and distorted, while the main body of the car—that is, the part between the 50 bolsters—may be uninjured. It is therefore evident that if the damaged end portions can be readily removed and replaced by new material the cars may be thus repaired in a very short time and at small expense. With this 55 end in view the side walls of the car beyond the bolsters are formed of the plates 6^a, which extend from the ends of the car only as far as the posts 3^a. The end floor-plates 5^a extend from the ends of the car only as far as the 60 supporting angle-beams 7. The lower members of the side trusses are divided by the posts 3^a into the parts 31 and 32, which are secured with their ends in engagement with said posts by the plates 33. The parts 32 ex- 65 tend from the said posts 3^a to the ends of the car and aid in supporting the end walls, the side wall plates 6^a, and the end floor-plates 5^a.

It is evident that the entire end of the car, consisting of the parts 5^a, 6^a, and 32, together with the end walls, end posts, end sills, and 70 the braces 30 and 33, may be removed from the main body of the car by cutting the rivets which unite these parts thereto.

Having thus described my invention, what I claim as new, and desire to secure by Letters 75 Patent, is—

1. In a metallic car, a transverse bolster-beam, a bent plate having a main portion secured to said beam and a portion projecting upward from said main portion, a flanged 80 beam secured to said upwardly-projecting portion, and a car-floor resting on one of the flanges of said flanged beam, substantially as described.

2. In a metallic car, a longitudinal center 85 sill, a transverse bolster-beam, and a bent plate, one portion of which is secured to said beam, and the remainder of which projects upward from said first portion, and is attached to a flanged floor-beam, substantially as de- 90 scribed.

3. In a metallic car, a transverse bolster-beam, a bent plate secured to said beam, flanged beams secured on both sides of said plate, and a car-body having a sloping floor 95 supported by said beams, substantially as de- scribed.

4. In a metallic car without side sills, a transverse bolster-beam, upright posts secured to the ends of said bolster-beam, a plate 100 secured to said bolster-beam intermediate the ends thereof, and a car-body hung upon said upright posts and partly supported by said plate, substantially as described.

5. In a metallic car-frame, a bolster-beam, 105 a bent plate having a main portion secured to the middle portion of said beam, and a portion projecting upward at an angle to said main portion, and a beam having a center portion secured to the projecting portion of 110 the bent plate and ends extending diagonally outward from said center portion, substan- tially as described.

6. In a metallic car, a bolster-beam, upright 115 posts secured to the ends thereof, a bent plate secured to said bolster-beam intermediate the ends thereof, a flanged beam secured to said bent plate, and a car-body suspended from said upright posts and having an inclined 120 floor-plate secured to said flanged beam, sub- stantially as described.

7. In a metallic car, a center sill, a trans- 125 verse bolster-beam resting upon said sill, a flat plate secured to and depending from said bolster-beam and carrying a side bearing, sub- stantially as described.

8. In a metallic car, a longitudinal sill, a car-bolster secured thereto and comprising a flanged beam, a flat plate secured to and de- pending from said beam and carrying a side 130 bearing, substantially as described.

9. A metallic car-frame, comprising longi- 135 tudinal flanged center sills, transverse chan- nel-bolster beams resting on said sills, de-

- pending plates carried by said bolster-beams, and side bearing-blocks carried by said depending plates, substantially as described.
10. In a metallic car, a longitudinal sill, a car-bolster secured thereto and comprising a plurality of channel-beams, flat plates secured to the backs of said beams and depending therefrom, and side bearing-blocks secured between the lower edges of said plates, substantially as described.
11. In a metallic car, a sloping floor supported by a floor-beam secured to the bolster and extending diagonally with respect to the floor, substantially as described.
- 15 12. In a hopper-bottom car, a car-body, a center sill passing through said car-body, a pair of bent floor-plates having sloping portions forming a longitudinal peak above said sill, upper vertical portions secured to each other, and lower vertical portions, and plates secured to said lower portions and extending to the bottom of the hoppers, substantially as described.
13. In a steel car, having its body divided 25 transversely into hoppers, the transverse dividing member being composed of sloping floor-beams and plates laid thereon, said floor-plates having vertical portions secured together, and angle-plates securing the vertical portions of the sloping floor-plates to the side walls of the car, substantially as described.
14. In a metallic car, a pair of longitudinal center sills, a car-bolster resting thereon and comprising a pair of beams, a depending plate carried by each bolster-beam, side bearings connecting said plates together, and means for securing said plates to the center sills, substantially as described.
- 40 15. In a metallic car, longitudinal end braces, a pair of center sills, a car-bolster resting thereon and comprising a pair of beams, a depending plate carried by each
- bolster-beam, side bearings connecting said plates together, said depending plates being 45 secured to the center sills and to the longitudinal end braces, substantially as described.
16. In a metallic car-frame, a longitudinal sill, a body-bolster secured above said sill, and comprising a pair of transverse beams, 50 and means for holding said beams in fixed relation to each other, substantially as described.
17. In a car, a pair of longitudinally-extending center sills, longitudinal side members, a pair of plates connecting each side member with its adjacent center sill, and a side bearing fitted between and spacing apart each pair of plates, substantially as described.
18. In a car, a longitudinal sill, a body- 60 bolster connected thereto and comprising a pair of beams held in fixed relation by means of a side bearing secured to said beams, substantially as described.
19. In a car, a longitudinal sill, a body- 65 bolster connected thereto and comprising a pair of beams, a pair of metal plates secured thereto, said plates being held in fixed relation at their bottoms by means of a side bearing, substantially as described. 70
20. A car having side wall-plates and a floor-plate which extend from the end of the car and terminate at the bolster, whereby the end of the car may be readily detached from the main body portion, substantially as 75 described.
21. A car having side wall-plates which extend from the end of the car and terminate at the bolster, whereby the end of the car may be readily detached from the main body portion, substantially as described. 80
